UNITED STATES PATENT OFFICE.

CARYL E. CHANEY, OF DETROIT, MICHIGAN.

ELECTRICAL HEATING UNIT.

1,206,510.

Specification of Letters Patent. Patented Nov. 28, 1916.

Application filed June 19, 1916. Serial No. 104,364.

To all whom it may concern:

- Be it known that I, CARYL E. CHANEY, a citizen of the United States of America, residing at Detroit, in the county of Wayne 5 and State of Michigan, have invented certain new and useful Improvements in Electrical Heating Units, of which the following is a specification, reference being had therein to the accompanying drawings.
- 10 The invention relates to electrical heating units of the armored resistor type, and it is the object of the invention to obtain various features of advantage as hereinafter set forth.
- 15 In the drawings: Figure 1 is a sectional elevation of the unit; Fig. 2 is a cross-section thereof; Fig. 3 is an enlarged cross-section through the refractory tube on which the resistor is wound; Fig. 4 is an elevation 20 thereof; and Fig. 5 is an elevation of the unit connected into an electric circuit.

My improved construction of heating unit is more particularly designed for use where it is desirable to limit the temperature in 25 all parts of the unit, so as to avoid danger of ignition of explosive vapors, or for other reasons. It is also an object to obtain a construction in which the maximum heat distribution may be obtained within given 30 space limits, and without exceeding the predetermined temperature. The unit is therefore preferably in the form of a hollow tube, dissipating heat both internally and externally, the internal heat being distributed by 35 convection and the external heat by radiation and convection.

In detail, A is a tubular refractory insulator body on which the heating resistor B is wound. This body is preferably formed 40 of porcelain, but inasmuch as such material is easily cracked by unequal temperatures in different portions thereof, special provision is made for avoiding this objection. Preferably the tube is formed of a plurality 45 of segments, said segments being preferably not greater than an angle of 120°, so as to limit the difference in length of their internal and external arcs. As shown, the segments B' B², etc., are provided with a 50 tongue and groove or lapped edge engagement C, so as to hold them from relative displacement. Externally, the segments are threaded and preferably with a double thread, so that the resistor may be wound in 55 one groove or thread to extend continuously

from one end of the tube to the other, and then be wound in the intermediate groove to extend back to the starting end. This arrangement is desirable, as it neutralizes any objectionable inductive effect.

The unit is armored both internally and externally, preferably with metallic tubing. The segments B' B² etc. are placed around the inner tube D, but are preferably separated therefrom by thermal insulation D'. 60 The outer tube E surrounds these segments B' B² etc., and a plastic filling F of an electrically insulating material having relatively high thermal conductivity is placed between these segments and the outer tube. 65 The reason for this construction is that the outer surface being greater in extent than the inner surface, there is a tendency for the latter to rise in temperature, which is avoided by the thermal insulation which 70 slows the rate of conduction.

To complete the unit, caps G and G' are arranged at the opposite ends of the unit to engage inner and outer tubes D and F. The terminals H and H' extend out through one 80 of these caps, being insulated by suitable bushings I and I'. As shown, the terminals are in the form of threaded studs, to which contact blades J and J' are attached, the latter being adapted for insertion into an 85 insulated holder K for the main conductors.

In use, the units may be mounted to extend perpendicularly to the member K and parallel to the wall L of the oven or chamber to be heated. When current is supplied, 90 the heat will be dissipated both externally and internally, the internal heat being distributed by circulatory air currents, as indicated by the arrows.

What I claim as my invention is:— 95

1. An electrical heating unit, comprising a tubular core member formed of a refractory insulating material formed in segments, said core being provided with a double thread or groove therein, a resistor wound in said thread to extend from one end to the other of the tube and to return in the intermediate groove to the original end, and an internal and external armor for 100 said tube.

2. An electrical heating unit, comprising an inner armor tube, an insulator tube formed in segments placed about said inner armor tube and in contact therewith, a resistor wound upon said segmental insulator 105 110

tube, an outer armor tube, and a refractory, solidified plastic insulation between the resistor and the outer tube.

3. An electrical heating unit, comprising 5 an inner armor tube, a refractory insulator tube formed of segments placed about said inner armor tube, said segments having complementary grooves forming a spiral thread thereabout, a resistor wound in said 10 thread, an outer armor tube, and a solidified plastic insulator between said resistor and outer tube.

4. An electrical heating unit, comprising 15 an inner armor tube, an insulator tube formed in segments arranged about said inner armor tube, said segments being provided externally with grooves forming complementary portions of a double thread, a resistor wound in said grooves from one end 20 of the tube to the other and returning through an intermediate groove, an outer armor tube, and solidified plastic insulation between said resistor and outer tube.

5. An electrical heating unit, comprising 25 an inner armor tube, an insulator tube

formed in segments arranged about said inner armor tube, said segments being provided externally with grooves forming complementary portions of a double thread, a resistor wound in said grooves from one end 30 of the tube to the other and returning through an intermediate groove, an outer armor tube, and means for decreasing the thermal conductivity to the inner tube in relation to the thermal conductivity to the 35 outer tube to equalize the temperatures thereof.

6. An electrical heating unit, comprising an inner armor tube, an insulator tube arranged about said armor tube, thermal insulation between said tubes, a resistor wound upon said insulator tube, an outer armor tube, and electrically insulating material having relatively high thermal conductivity between said insulator tube and outer 45 armor tube.

In testimony whereof I affix my signature.

CARYL E. CHANEY.
